UNITED STATES PATENT OFFICE.

JOHN SHINN AND OLIVER M. FAGLEY, OF PHILADELPHIA, PENNSYLVANIA, ASSIGNORS OF ONE-HALF TO ABBOTT F. FULLER AND WILLIAM N. MARCUS, BOTH OF SAME PLACE.

CURTAIN-FIXTURE.

SPECIFICATION forming part of Letters Patent No. 359,896, dated March 22, 1887.

Application filed November 19, 1886. Serial No. 219,426. (No model.)

To all whom it may concern:

Be it known that we, JOHN SHINN and OLIVER M. FAGLEY, citizens of the United States, residing at Philadelphia, in the county of Philadelphia and State of Pennsylvania, have 5 jointly invented a new and useful Improvement in Curtain-Fixtures, of which the following is a specification.

Our invention relates to improvements in fixtures for connecting or hanging curtains to rings that slide on poles; and the object of our invention is to so connect the curtain to sliding rings that when the rings are forced together the curtain will fold in plaits; and our 15 invention consists in running in the upper hem of a curtain a jointed bar made of wood and paper or of metal, each section of the jointed bar being connected in the center of its length to a sliding ring on the curtain-pole, all as will be hereinafter described, reference being had 20 to the annexed drawings, making a part of this specification, in which—

Figure 1 is a front view of a curtain-pole, brackets, sliding rings, and our improvement. 25 Fig. 2 is a top view of parts shown in Fig. 1 with the jointed bar partially closed. Fig. 3 shows a side and edge view of the jointed bar. Fig. 4 shows a side and edge view of the jointed 30 bar partially closed. Fig. 5 shows side and edge views of a section of the jointed bar, one of said sections being formed of wire. Fig. 6 shows a jointed bar made of wire.

Similar letters refer to similar parts throughout the several views.

35 A represents an ordinary curtain-pole; B B, the brackets; D D, the sliding rings; E, the jointed bar, which we prefer to make of wood in sections. On each side of these sections we glue a strip of Manila paper, cloth, or leather, put on as is shown in the edge view 40 of Fig. 3—that is, the paper forms the joints—and at alternate sides it is bowed, as shown at

SS. At the center of the length of each section is cut a hole, *a a*, by means of which and a cord, hook, or split ring the bar E is connected to the rings D D, as shown in Fig. 1.

Fig. 6 shows a jointed bar made of eight wire links. One of the links is shown in Fig. 5. This bar is connected to the rings D D from the eyes *a a*.

50 To connect our improved jointed bar to a curtain, we make a hem on the upper end of the curtain, and of a width that the bar will slide into the hem. Holes are then cut in the curtain to correspond with the holes *a a* in the bar. If a bar as shown in Fig. 6 is used, we line the inside of the hem with heavy cotton drilling, to prevent the wire joints from pushing through the curtain fabric. When the curtain is “drawn,” by sliding the rings D D 55 together, as shown in Fig. 2, the jointed bar E will fold and plait the curtain in a manner similar to a folding fan.

The drawings show the representation of but one bar; but it is obvious that two bars 65 may be connected to one pole. We show the bar made in eight sections; but more or less may be used.

The bar E is shown as connected to the rings D D by intermediate connections, *b*; but they 70 may be connected by a hook forming a part of the sliding ring.

We claim—

In a curtain-fixture, the combination of a 75 jointed bar, E, to which the curtain is attached, sliding rings D D, connected to said jointed bar, and curtain-pole A, substantially as shown and described.

JOHN SHINN.
OLIVER M. FAGLEY.
